UNITED STATES PATENT OFFICE.

CHARLES P. MARSHALL, OF MEMPHIS, TENNESSEE.

BOILER.

SPECIFICATION forming part of Letters Patent No. 462,718, dated November 10, 1891.

Application filed December 23, 1890. Serial No. 375,590. (No model.)

To all whom it may concern:

Be it known that I, CHARLES P. MARSHALL, a citizen of the United States, residing at Memphis, in the county of Shelby and State of Tennessee, have invented certain new and useful Improvements in Boilers, of which the following is a full, clear, and exact specification.

My invention consists in certain features 10 of novelty hereinafter fully described in connection with the accompanying drawings, which form part of this specification, and more particularly pointed out in the claims.

In the said drawings, Figure I is a vertical 15 section of the preferred form of my improved apparatus. Fig. II is a horizontal section taken on the line II II, Fig. I. Fig. III is a detail view hereinafter described. Fig. IV is a vertical section of a modified form.

Like signs of reference refer to like parts 20 throughout the several views.

1 is the fire-box, having any suitable grate 2 and fire-door 3, whose side walls are composed of plates 4, constituting the inner wall of an 25 annual water-leg 5, and secured to the upper ends of these plates is a crown-sheet 6, which constitutes the upper side of the fire-box. Arranged above this crown-sheet is a smoke-sheet 7, which is of larger diameter than the 30 crown-sheet, and which is secured at its periphery to the inner wall 8 of a combustion-chamber 9. This combustion-chamber has communication with the fire-box through ascending fire tubes or flues 10, whose upper 35 and lower ends are expanded or riveted in the said smoke-sheet 7 and crown-sheet 6, respectively. The lower ends of the plates 4 are connected by means of an annular or ring-shaped plate 11 to the exterior boiler 40 sheets or plates 12, which extend upward within a short distance of the smoke-sheet 7, where they join with a flaring ring 13, and this ring is surmounted by plates 14, which latter, together with an annular top plate or ring 15 45 and the wall 8 of the combustion-chamber, forms a steam space or dome 16.

Suitably secured to the wall 8 of the combustion-chamber, at a suitable distance above the smoke-sheet 7, is an annular flange 17, 50 and upon this flange is removably seated a feed-water-heating chamber 18. This chamber 18 is preferably composed of a side ring 19 and inwardly-dished top and bottom plates 20 and 21, respectively. The plates of

this chamber are dished or concaved for a 55 two-fold purpose: first, for the sake of the great strength that such a formation affords, and, second, for causing the products of combustion as they ascend through the fire-tubes 10 to be deflected downward again 60 toward the outer edge of the smoke-sheet 7, so that such products will readily pass from the combustion-chamber through descending flues 22. These flues 22 are preferably 65 larger in diameter than the flues 10 and arranged vertically within the water-space of the boiler at suitable intervals apart and have their upper and lower ends expanded or riveted in the smoke-sheet 7 and bottom ring or plate 11, respectively. The boiler proper— 70 that is to say, the steam dome or space 16 and the water-space surrounded by the exterior boiler-plates 12—is provided with a casing or jacket 23, which completely encompasses it and preferably follows its exterior contour, 75 there being a slight space between it and the sides of the boiler proper for the upward passage of the products of combustion to the stack 24, mounted on the top of the casing. This casing also extends downward below the 80 water-leg 5, and the walls or plates 4 of the fire-box extend down an equal distance and form with the casing the breeching or smoke-box 25, into which the descending flues 22 empty. The products of combustion upon 85 entering the said breeching immediately begin an upward course between the exterior boiler-plates and the casing 23, and in such upward course they directly impinge the under side of the flaring ring 13, heating it to 90 an intense degree, and then pass on and envelop the steam-dome, and finally exit via the stack. The feed-water-supply pipe 26, provided with suitable checks and cocks, has a branch 27, leading directly into the water-leg 95 5 and adapted to admit water thereinto when desired by turning the cock 28, and it also has a branch 29, which extends upwardly and then horizontally through the boiler-plates and casing and communicates with the chamber 18 for supplying water to the latter to be heated preparatory to its admission into the boiler proper. The feed-water leaves the chamber 18 via pipe 30, which likewise passes through the boiler-plates and casing and then 100 descends to a lower level, where its end dips into a vertical tubular mud-drum 31, the upper part of which latter is provided with a 105

valve-guarded pipe 32, leading into the water-leg 5. The lower end of the mud-drum is preferably made cylindrical, so that the sediment may be readily blown off through the 5 blow-off pipe 33, and this blow-off pipe 33 is preferably connected by pipe 34 with the bottom of the boiler, as shown in dotted lines in Fig. I, so that sediment in the latter also may be removed. The horizontal portion of the 10 pipes 29 30 pass through short tubes 35, expanded in the plates 8 14. The tubes 35 thus serve as stay-bolts for sustaining the walls of the boiler and at the same time form convenient means for the passage of the pipes 15 29 30 to the chamber 18 and prevent the steam or hot water in the boiler from coming into contact with the said pipes and thereby being condensed or chilled. The top plate 15 and side plates 12 may be provided at 20 suitable intervals with any desirable and suitable form of hand-holes 36 for affording easy access to the interior of the boiler for cleaning, inspecting, &c., and the chamber 18 may also be provided with similar hand-holes 37 25 for a like purpose, and I prefer to provide such chamber also with a central hand-hole 38, formed by expanding a ring 39 in its top and bottom plates, and having a suitable cover or lid 40, whereby the parts may be 30 cleaned and access to the chamber below may be had without the necessity of removing the chamber 18. I prefer to make the chamber 18 of such size that it will fit the walls 8 of the combustion-chamber, and thus shut off 35 communication between the fire-box and stack, excepting *via* the return or descending flues 22 and casing; but it will of course be understood that the bottom plate 21 only need be equal in diameter to that of the combustion-chamber in order to accomplish the said 40 result, and that the said chamber 18 therefore might be of smaller relative diameter without departing materially from the spirit of my invention; but it is of course advantageous, for obvious reasons, to have the superficial area of this chamber as large as possible. The plates or walls of the boiler and also the plates of the chamber 18 may be 45 braced or re-enforced where convenient and desirable by any suitable number of tie bolts or rods 41, having their ends riveted or otherwise secured thereto. In the chamber 18, however, I prefer to employ, instead of the solid tie-rods, short tubes or pipes 41^a, which have their upper and lower ends expanded or riveted in the plates of the said chamber, as 50 shown in Fig. I, and which, while they serve the same purpose as the solid rods 41, also facilitate in blowing out the tubes and flues 55 10 22. For this latter purpose the tubes 41^a are preferably equal in number to the number of tubes and flues 10 22 employed, so that any suitable steam-nozzle (not shown) may be inserted in the upper ends of the tubes 41^a, and discharging downward blow the soot from 60 the tubes and flues below into the smoke-box and fire-chamber, from whence it may be re-

moved, and to make the force of the steam more effective the tubes 41^a are arranged so as to be coincident with the tubes and flues 70 10 22. The upper ends of the tubes 41^a are normally closed by means of a plate 41^b, Fig. III, which is provided with a central opening c to admit the cover 40 and openings d for the admission of the hand-hole mechanism. 75 It may also be provided with lifting-rings c. It is intended that the water-line shall be maintained at a point above the chamber 18, as shown; but this of course may be varied in the discretion of the operator. 80

In the modified form of my device illustrated by Fig. IV the construction is the same as that already described, with the exception that the water-space through which the tubes 10 pass and such tubes are omitted, thus leaving the chamber 18 to compose the crown of the fire-box as well as that of the combustion-chamber. This form also differs from the other, in that the chamber 18 is provided with solid tie-rods 41, and consequently has not 90 the cover-plate 41^b; but, if desired, the chamber 18 in this form also may be constructed like that in the other form. This latter arrangement answers the purpose when the apparatus is constructed on a smaller scale. 95

Having thus described my invention, the following is what I claim as new therein and desire to secure by Letters Patent—

1. The combination, in a steam-boiler, of the fire-box, the boiler proper surrounding said fire-box, the stack or uptake, a feed-water-heating chamber surrounded by the boiler proper and arranged before the steam-space thereof and closing communication between said fire-box and stack, and return smoke-flues leading from undersaid feed-water chamber and communicating with the stack, substantially as set forth.

2. The combination, in a steam-boiler, of the boiler proper, the fire-box surrounded by said boiler proper, the stack, a feed-water-heating chamber surrounded by said boiler proper and arranged before the steam-space thereof and closing communication between said stack and fire-box, and smoke-flues leading from under the feed - water chamber through the boiler proper and communicating with the stack, substantially as set forth.

3. The combination, in a steam-boiler, of the fire-box, the stack, a feed-water-heating chamber arranged between said fire-box and stack, a steam and water chamber surrounding the said feed-water chamber and forming a combustion-chamber between the said latter chamber and fire-box, flues connecting the fire-box with said combustion-chamber, and flues passing through the steam and water chamber and connecting said combustion-chamber with the stack, said feed-water chamber being arranged below the top of said steam and water chamber, substantially as set forth.

4. The combination, in a steam-boiler, of the fire-box, the stack, the boiler proper sur-
